(57) **CLAIM**

I claim the design for a folding loop string puzzle, as shown and described.

DESCRIPTION

FIG. 1 is a front elevational view of the folding loop string puzzle of the present invention.

FIG. 2 is a rear elevational view thereof.

FIG. 3 is a left side elevational view thereof, the right side being a mirror image of the left side.

FIG. 4 is a top plan view thereof.

FIG. 5 is a bottom plan view thereof.

FIG. 6 is a left side perspective view thereof, in the folded position.

FIG. 7 is a front elevational view thereof in the folded position.

FIG. 8 is a rear elevational view thereof in the folded position.

FIG. 9 is a left side elevational view thereof in the folded position, the right side being a mirror image of the left side.

FIG. 10 is a top plan view thereof in the folded position; and, FIG. 11 is a bottom plan view thereof in the folded position.
